UNITED STATES PATENT OFFICE.

ISAAC N. FOOTE, OF MIDDLETOWN, OHIO.

TRUSS-PAD.

SPECIFICATION forming part of Letters Patent No. 311,739, dated February 3, 1885.

Application filed April 28, 1884. (No model.)

To all whom it may concern:

Be it known that I, ISAAC N. FOOTE, of Middletown, Butler county, Ohio, have invented certain new and useful Improvements in Truss-Pads, of which the following is a specification.

This invention relates to the general construction and arrangement of parts in truss-pads; and it will be readily understood from the following description, taken in connection with the accompanying drawings, in which—

Figure 1 is a side elevation of a truss-pad illustrating my present invention; Fig. 2, a vertical section of the same, and Fig. 3 a plan of the same.

In the drawings, A represents a hollow shell of soft rubber or analogous material, and having substantially the form of a hemisphere with a concave face. B is the button of the truss seated within the concavity of the shell, and projecting above the surrounding rim C. D is a screw in the back of the pad, by which it may be secured to the strap attachment. The button B presses back the protrusion, while the rim C exerts a pressure independent of the button upon the surrounding muscular tissues. The shell of the pad is air-tight, whereby it becomes naturally elastic; but I fill the chamber with glycerine or other suitable liquid, and thus provide a peculiar adaptability combined with an elasticity due to the elasticity of the substance of the shell. The screw D has its head inside the shell of the pad, and it is made tight by nut and washer. It may be provided with any desired means for making connection with the strap. I give to the button B a further element of elasticity by inserting under it a spring, G, and attaching it articulately to the shell. The joint of articulation is a hinge, which should be constructed with considerable looseness, so as to permit a small amount of tipping in every direction. The button may thus adjust itself in direction and pressure independent of the rim C.

In practice I mold the rubber shell to form, and secure within the concavity of the same a cup, F, to which I attach the button by hinging, as before mentioned. This cup I secure within the concavity of the shell by means of cement or otherwise, as may be found desirable. I further cause the truss-pad to form a generator of electricity. The cup F, I form of copper. The button B, I form of hard rubber

or other insulating material. Beneath the button I place a zinc lining, H, which is not allowed to come in contact with the copper cup. 55 The zinc lining has a projection, I, through the button, forming an electrode upon the outer face of the button. Another electrode, J, in the face of the button connects with the cup through the medium of the spring G, and it is 60 not allowed to make contact with the zinc lining of the button. A wad, K, of absorbent material, lies within the cup in contact with both of the elements of the battery, and it contains the exciting-liquid. Other material 65 than those mentioned may be used for the battery elements, and they may be otherwise disposed within the cup.

When the truss-pad is applied to the person, the initial pressure comes upon the button and 70 presses it backwardly more or less into the concavity of the pad. This backward pressure serves to displace a portion of the liquid contents of the pad and to cause the facial rim to expand forwardly into a perfect fit against 75 the person, and the pressure which the button receives is transmitted through the solid inelastic contents of the pad.

Truss-pads have been filled with air, which endowed them with an elasticity due to the 80 elasticity of the air. In my device the liquid is inelastic, and serves, on the displacement principle, to cause the pad-rim to adapt itself perfectly to the person.

In a truss-pad heretofore invented by me I 85 made use of a hollow rubber hemisphere with a hard button seated upon the convex face thereof. The pad was to be filled with air or liquid, and if the pad was partially emptied the button could recede somewhat into the face 90 of the pad, forming a concave seat therein. Such concave facial seat was formed by the partial vacuum within the pad, and the action of the pad under pressure was somewhat erratic, there being no defined location for the 95 facial concavity. In the present invention I have remedied this defect by molding the pad with a permanent facial concavity, resulting in a well-defined and permanent ring closely surrounding the button.

I claim as my invention—

1. In a hollow truss-pad, a permanent facial concavity and peripheral facial ring, a back of soft rubber or analogous material, and a

hard button seated within the concavity, combined substantially as and for the purpose set forth.

2. In a truss-pad, the combination of a shell of soft rubber or analogous material having a facial concavity, a cup secured within and forming a lining for said concavity, and a hard button articulated to said cup, substantially as and for the purpose set forth.

10 3. The combination of a truss-pad having a facial concavity, a cup secured within and

forming a lining for said concavity, a cover articulated to said cup, and forming the button of the truss-pad, electrodes presenting at the faces of said button, and an electric battery beneath said cover, and joined up with said electrodes, substantially as and for the purpose set forth. 15
